ADOLF GANZFRIED AND WILLIAM B. CLARY, OF LOS ANGELES, CALIFORNIA.

SMOKER'S MOUTHPIECE.

Application filed July 21, 1926. Serial No. 123,893.

Our invention is a smoker's mouthpiece adapted for use with cigarettes and may be made in the form of a cigarette holder.

An object of our invention is to make a smoker's mouthpiece particularly in the form of a cigarette holder so that the smoke will have to traverse an elongated passage from the cigarette to the mouth end of the mouthpiece, thereby cooling the smoke.

10 A further object of our invention is to form the mouthpiece with a series of longitudinal passages connected together at the ends so that the smoke from a cigarette holder at the end of the mouthpiece will be required to traverse the longitudinal passage in a zig zag path, thereby allowing cooling of the smoke.

15 In one form of our construction we have the mouthpiece made with a series of longitudinal grooves connected together at their ends, the end of one of the grooves being connected by a bore to the mouth end of the mouthpiece and the other end of the continuous passage formed by the grooves is connected by a bore to a cigarette holder. The mouthpiece having the grooves on the outside surface is covered by a sleeve screw threaded into engagement with the cigarette holder, thereby forming an air-tight closure 30 for the passages but allowing removal of the closure for cleaning of the various grooves.

20 In another form of our construction we have a series of fine longitudinal bores extending lengthwise of a stem piece, these 35 being arranged preferably in a circle and having connections formed on the ends with a mouthpiece and a cigarette holder so as to connect adjacent bores one to the other.

25 The mouthpiece is provided with a centering attachment so that it may be properly positioned relative to the stem. The holder is also provided with a somewhat similar centering arrangement allowing its detachment. Therefore the bores in the stem may 40 readily be cleaned by passing a cleaning implement therethrough.

Our invention is illustrated in the following drawings, in which;

Figure 1 is a perspective view of our 50 smoker's mouthpiece with a cigarette in the holder;

Fig. 2 is a longitudinal section on the line 2-2 of Fig. 1 in the direction of the arrows;

Fig. 3 is a side elevation enlarged, showing

the longitudinal grooves on the stem part of 55 the mouthpiece;

Fig. 4 is a cross section of Fig. 3 on the line 4-4 in the direction of the arrows;

Fig. 5 is a cross section on the line 5-5 of Fig. 3 in the direction of the arrows; 60

Fig. 6 is a side elevation of a modification in which the stem part is separable from the mouthpiece and the holder end, and has a smoke passage formed by a series of bores 65 extending longitudinally through the stem;

Fig. 7 is a longitudinal section of Fig. 6 on the line 7-7 in the direction of the arrows; 70

Fig. 8 is a cross section of Fig. 7 on the line 8-8 in the direction of the arrows. 75

In the construction of Figs. 1 to 5, a stem section 1 has a series of longitudinal grooves 2 formed therein, these grooves being connected by transverse grooves 3 and 4 at each end so as to form a zig zag path for smoke. 80 The mouth end 5 has a bore 6 therethrough terminating in the end of one of the grooves. A cigarette holder 7 in the form of a tube is attached to the end of the stem opposite the mouth end and a bore 8 extends from the 85 end of one of the grooves to the base of the cigarette holder. This particular groove would be at the termination of the zig zag passage formed by the longitudinal and the short transverse grooves. 85

The cigarette holder structure is provided with screw threads 9 and a sleeve 10 is fitted over the stem, being passed over the mouth end and threaded on the threads 9. This sleeve is preferably slightly tapered inwardly, contacting with the tapered surface 11 on the end of the stem adjacent the mouth end. Therefore when the sleeve is threaded tightly on the threads 9 this forms a substantially air-tight seal at such threads and 90 at the slightly tapered portion 11. 95

In this type of smoker's mouthpiece it will be apparent that the smoke from a cigarette must traverse an extended passage through the grooves on the periphery of the stem and that the sleeve may be readily detached to allow cleaning of these grooves. It is manifest that the stem and the sleeve may be made of any suitable material. 100

In the construction of Figs. 6 and 7, the 105 stem 12 is provided with a series of bores 13 extending from end to end and the mouth end 14 has a bore 15 extending therethrough.

There are a series of short transverse semi-circular grooves 16 registering with similar grooves 17 on the end of the stem section. The bore 15 connects with one of the longitudinal grooves 13.

A series of grooves 18 and 19 are formed in the end of the stem opposite the mouthpiece and in the cigarette holder 20. These grooves connect adjacent longitudinal bores 13 alternately so as to make an elongated zig zag passage for smoke from the bore 15 to the bore 21 through the cigarette holder base 22.

In this construction it is necessary to have plugs 23 or the like on the mouthpiece and end 24 or the like on the cigarette holder and fitting in complementary recesses in the stem to properly locate and center the bores in the mouthpiece end and in the cigarette holder end with their proper grooves. These are held in place preferably by a tight friction fit.

In the construction as illustrated in Figs. 6 and 7, when it is desired to clean the smoker's mouthpiece the mouthpiece end and the cigarette holder end may be removed from the stem and the longitudinal bores 13 cleaned by any suitable implement. The short connecting grooves in the ends of the stem and the ends of the mouthpiece section and cigarette holder section will likewise be readily cleaned.

From the above description it will be seen that we have developed a simple type of smoker's mouthpiece which may be designated as a cigarette holder in which the smoke must follow a path of considerable length before entering the mouth, thus cooling the smoke, and moreover, this provides a device which may be readily cleaned.

It will be noted in the construction of Figs. 1 through 5 that the end of the stem adjacent the cigarette holder is screw threaded and the end adjacent the mouthpiece is

tapered. Therefore when the cylindrical sleeve 10 is inserted over the mouthpiece and screwed tight to the threads, it forms a smoke tight seal at both ends of the stem and moreover by this construction the sleeve is readily removable for cleaning.

It is manifest that the details of construction may be considerably changed both generally or specifically, to form different types of mouthpiece constructions. Such changes would be within the spirit of our invention as set forth in the description, drawings and claims.

Having described our invention, what we claim is:

1. A smoker's appliance comprising in combination, a cylindrical stem having a mouth piece at one end and a cigarette holder fixedly secured at the other end, a series of connecting grooves on the peripheral surface of the stem, said grooves being connected to smoke passages through the mouth piece and to the cigarette holder, screw threads at the holder end of the stem, and a sleeve insertable over the mouth piece and the stem and screwed on said threads.

2. A smoker's appliance comprising in combination, a cylindrical stem having a mouth piece at one end and a cigarette holder fixedly secured at the other end, there being screw threads adjacent the holder end, a series of grooves on the periphery of the stem connected to smoke passages through the mouth piece and to the holder, the stem at the mouth piece end having a tapered surface, a sleeve insertable over the mouth piece and the stem and screwed to the said threads, the mouth piece end of the sleeve having a taper to form an air tight seal with the tapered surface of the stem.

In testimony whereof we have signed our names to this specification.

ADOLF GANZFRIED.
WILLIAM B. CLARY.
